UNITED STATES PATENT OFFICE.

ALBON CHASE PETERSON, OF ARCADIA, LOUISIANA, ASSIGNOR OF ONE-HALF
TO THOMAS J. BROOKS, OF SAME PLACE.

FENCE-POST.

SPECIFICATION forming part of Letters Patent No. 398,078, dated February 19, 1889.

Application filed November 21, 1888. Serial No. 291,419. (No model.)

To all whom it may concern:

Be it known that I, ALBON CHASE PETERSON, a citizen of the United States, residing at Arcadia, in the parish of Bienville and State 5 of Louisiana, have invented new and useful Improvements in Fence-Posts, of which the following is a specification.

The invention relates to improvements in fence-posts; and it consists in a certain novel 10 construction and combination of devices, fully described hereinafter in connection with the accompanying drawings, and specifically pointed out in the appended claim.

In the drawings, Figure 1 is a perspective 15 view of the improved post. Fig. 2 is a side view, partly in section, of the same arranged in the operative position in the ground.

Referring by letter to the drawings, A designates the anchor, which is arranged in the 20 ground on the line of fence, and is provided with the flat blade B, tapered toward its lower end, and arranged with its width coincident with the line of the fence. At the upper end of the blade, on opposite sides, are the shoulders C C, which bear on the surface of the 25 ground, as shown in Fig. 2, and steady the post laterally, and vertical parallel ears D D extend upward from the upper end of the blade about four inches apart.

30 The upright E, which is formed separate from the anchor, is provided at its lower end with the parallel depending ears F F, which fit between the vertical ears D D and bear, respectively, against the same, and bolts or screws G G engage registering apertures d d and f f in the said contacting ears to secure the upright firmly to the anchor.

The post is preferably reduced at an intermediate point to form the neck H, above and 40 below which are the notches or rail-openings I I, and at the lower edges of the said notches are vertical flanges or lips K K. The rails L L, portions of which are shown in Fig. 2, are fitted

at their ends in the notches, and are held from being pushed out of the same by the said 45 flanges or lips K K, and wedges M M are inserted between the upper edges of the rails and the upper sides of the notches to hold the rails firmly pressed against the bottoms of the notches and prevent them from being raised. 50

The entire post is preferably formed of cast metal, the two separable portions of which are connected after the anchors are fixed in the ground; but the upper portion or upright may be formed of wood, in which case its 55 lower end is fitted between the vertical ears of the anchor, in the manner above described, and secured by bolts or screws.

It will be noted that the parallel ears D D on the anchor are arranged at right angles to 60 the width of the blade, and therefore at right angles to the line of fence, and therefore it will be seen that the longitudinal strain on the fence causes the post to bear against one ear or the other, and thereby prevents undue 65 straining of the screws or bolts which secure the upright to the anchor.

Having thus described the invention, I claim—

In a fence-post, the combination, with the 70 anchor secured in the ground and provided with the vertical ears D D at right angles to the line of the fence, of the upright provided with the depending parallel ears F F, fitting between the ears D D and provided with 75 apertures f f, registering with apertures d d in the ears D D, and the bolts or screws engaging the said registering apertures, substantially as specified.

In testimony that I claim the foregoing as 80 my own I have hereto affixed my signature in presence of two witnesses.

ALBON CHASE PETERSON.
